COMBINED HOLDER FOR CAMERA FILTERS
AND CASE THEREFOR

Clarence C. Brown, Bakersfield, Calif.

Application January 6, 1954, Serial No. 28,389

Term of patent 3½ years

(Cl. D61—1)

To all whom it may concern:

Be it known that I, Clarence C. Brown, a citizen of the United States and a resident of Bakersfield, California, have invented a new, original, and ornamental Design for a Combined Holder for Camera Filters and Case Therefor, of which the following is a specification, reference being had to the accompanying drawing, forming a part hereof.

Fig. 1 is a top perspective view of a combined holder for camera filters and case therefor showing my new design.

Fig. 2 is a top plan view thereof.

Fig. 3 is a bottom plan view thereof.

Fig. 4 is a side elevational view thereof.

Fig. 5 is a bottom perspective view of the holder portion thereof.

Fig. 6 is a side elevational view of the holder portion thereof.

Fig. 7 is a top perspective view thereof.

Fig. 8 is a bottom plan view of the holder portion thereof, and

Fig. 9 is a top perspective view of the case portion thereof.

I claim:

The ornamental design for a combined holder for camera filters and case therefor, substantially as shown.
